CLAIM

The ornamental design for a glasses, as shown and described.

DESCRIPTION

FIG. 1 is a front perspective view of a glasses, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The broken lines in the drawings depict portions of the glasses that form no part of the claimed design. The dash dot dash broken lines shown in FIG. 1 and FIG. 9 are for the purposes of disclosing areas of enlargement that form no part of the claimed design.

1 Claim, 9 Drawing Sheets
